FIG.- 3

SIDNEY J. TEMPLE
INVENTOR

BY ATTORNEY

UNITED STATES PATENT OFFICE

2,625,634

ELECTRIC HEATING

Sidney J. Temple, Swissvale, Pa., assignor to
 Edwin L. Wiegand Company, Pittsburgh, Pa.,
 a corporation of Pennsylvania

Application August 30, 1950, Serial No. 182,359

8 Claims. (Cl. 201—67)

1

My invention relates to electric heating, and the principal object of my invention is to provide an improvement in sheathed resistor electric heaters particularly in their terminal portions.

In the drawing accompanying this specification and forming a part of this application I have shown, for purposes of illustration, one mode of carrying my invention into practice, and in this drawing:

Figure 1 is a side view of an electric heater according to the selected mode;

Figure 2 is an enlarged central longitudinal section through one of the terminal portions of the heater of Figure 1;

Figure 3 is a section on the line 3—3 of Figure 2; and

Figure 4 is a partial side elevation of the terminal extension shown in section in Figure 3.

For purposes of illustration I have shown a heater 10 of a type commonly known as a hair-pin immersion heater, designed to be immersed in the liquid to be heated, and comprising a substantially circular tubular sheath 11, a helical resistor 12 extending longitudinally of the sheath 11, terminal pins 13 to which the ends of the resistor 12 are connected, and suitable refractory material 14, such as magnesium oxide, embedding the resistor 12 and the inner portions of the terminal pins 13.

According to the present embodiment of my invention, welded or otherwise secured fluid-tight to the ends of the sheath 11, are tubular fittings 15 each provided with a flange 16, a smooth section 17, and a screw-threaded section 18, and screw-threaded to the terminal pins 13 are terminal extensions 19 each extending substantially beyond the outer end of the respective fitting 15, provided on the extending portion with a suitable screw thread 20, and provided within the fitting 15 with a flat-sided section 21 and the knurled sections 22 and 23.

In the present embodiment, after the fittings 15 and terminal extension 19 have been applied, at each terminal the outer portion of the terminal pin 13 and the inner portion of the terminal extension 19 to and including the flat-sided section 21, are embedded in further refractory material 22, preferably a suitable cement, such as a composition comprising granular zircon and a suitable clay, and the cement is set, as by firing at a suitable temperature.

Then there is introduced into the remaining space within the fitting 15, a quantity of a suitable sealing material 23, such as that described

2

in the copending application of Frederick E. Hasley, filed May 21, 1949, Serial Number 94,649, and into this is introduced a ceramic bushing 24, after which a nut 25 is applied to the screw thread 20 of the respective terminal extension 19, and tightened to seat the bushing 24 and hold it in position, preferably with a suitable washer 26 interposed between the nut 25 and the bushing 24.

10 The described heater may conveniently be installed by projecting the two ends of the heater through apertures 27 in the wall 28 of the tank or duct or other container for the liquid to be heated, into position with the smooth sections 17 of the fittings 15 within the apertures 27 and the flanges 16 engaging the inner face of the wall 28, preferably with gaskets 29 interposed, then applying nuts 30 to the threaded sections 18 of the fittings 15 and drawing these nuts 30 against the outer face of the wall 28, preferably with suitable washers 31 interposed, thus drawing the fitting flanges 16 into liquid-tight relation with the inner face of the wall 28.

Thereupon electrical connection may be made 25 by applying electrical conductors 32 to the exposed portions of the threaded sections 20 of the terminal extensions 19, and securing the conductors in position by means of nuts 33, preferably with washers 34 interposed, the cement 22 serving to retain the extensions 19 against rotation, particularly by reason of the irregular cross-section provided by the flat-sided sections 21 and the knurled sections 35.

30 However, as will be understood by those skilled in the art, various changes may be made, within the scope of my invention, and thus my invention is not to be regarded as limited to the present disclosure, but to be commensurate with the scope of the claims, and I claim:

40 1. An embedded-resistor electric heater comprising an open-ended tubular sheath, an electrical resistor disposed within said sheath, a resistor terminal member secured to one end of said resistor, an electrically insulating and heat conducting refractory material embedding said resistor in said sheath, at least a portion of the length of said terminal member being free of said embedding refractory material and accessible through the open end of said sheath, a tubular fitting secured to the open end of said sheath and continuing the tubular length of said sheath, said tubular fitting being adapted to extend through a wall, a terminal extension secured to the said terminal member and extending outwardly from the open end of said sheath

and through said tubular fitting, at least a part of said terminal extension being irregular in cross-section, a refractory material embedding at least a portion of the irregular cross-sectional part of said terminal extension and thereby holding said terminal extension against rotation relative to said sheath, an external flange on said tubular fitting adapted to engage one face of a wall through which the tubular fitting extends, and an external threaded section on said tubular fitting in advance of said flange for receiving a nut for drawing said flange into sealing relation with said wall face.

2. An embedded-resistor electric heater comprising an open-ended tubular sheath, an electrical resistor disposed within said sheath, a resistor terminal member secured to one end of said resistor, an electrically insulating and heat conducting refractory material embedding said resistor in said sheath, at least a portion of the length of said terminal member being free of said embedding refractory material and accessible through the open end of said sheath, a tubular fitting secured to the open end of said sheath and continuing the tubular length of said sheath, said tubular fitting being adapted to extend through a wall, a terminal extension secured to the said terminal member and extending outwardly from the open end of said sheath and through said tubular fitting, at least a part of said terminal extension being irregular in cross-section, a cement-like refractory material embedding at least a portion of the irregular cross-sectional part of said terminal extension and thereby holding said terminal fitting against rotation relative to said sheath, an external flange on said tubular fitting adapted to engage one face of a wall through which the tubular fitting extends, and an external threaded section on said tubular extension in advance of said flange for receiving a nut for drawing said flange into sealing relation with said wall face.

3. An embedded-resistor electric heater comprising an open-ended tubular sheath, an electrical resistor disposed within said sheath, a resistor terminal member secured to one end of said resistor, an electrically insulating and heat conducting refractory material embedding said resistor in said sheath, at least a portion of the length of said terminal member being free of said embedding refractory material and accessible through the open end of said sheath, a tubular fitting secured to the open end of said sheath and continuing the tubular length of said sheath, said tubular fitting being adapted to extend through a wall, a terminal extension secured to the said terminal member and extending outwardly from the open end of said sheath and through said tubular fitting, at least a part of said terminal extension being irregular in cross-section, a set cementitious refractory material embedding at least a portion of the irregular cross-sectional part of said terminal extension and thereby holding said terminal extension against rotation relative to said sheath, an external flange on said tubular fitting adapted to engage one face of a wall through which the tubular fitting extends, and an external threaded section on said tubular fitting in advance of said flange for receiving a nut for drawing said flange into sealing relation with said wall face.

4. An embedded-resistor electric heater comprising an open-ended tubular sheath, an electrical resistor disposed within said sheath, a re-

sistor terminal member secured to one end of said resistor, an electrically insulating and heat conducting refractory material embedding said resistor in said sheath, at least a portion of the length of said terminal member being free of said embedding refractory material and accessible through the open end of said sheath, a tubular fitting secured to the open end of said sheath and continuing the tubular length of said sheath, said tubular fitting being adapted to extend through a wall, a terminal extension secured to the said terminal member and extending outwardly from the open end of said sheath and through said tubular fitting, at least a part of said terminal extension being irregular in cross-section, a refractory material embedding at least a portion of the irregular cross-sectional part of said terminal extension and thereby holding said terminal extension against rotation relative to said sheath, a seal for the open end of said tubular fitting, an external flange on said tubular extension adapted to engage one face of a wall through which the tubular fitting extends, and an external threaded section on said tubular fitting in advance of said flange for receiving a nut for drawing said flange into sealing relation with said wall face.

5. An embedded-resistor electric heater comprising an open-ended tubular sheath, an electrical resistor disposed within said sheath, a resistor terminal member secured to one end of said resistor, an electrically insulating and heat conducting refractory material embedding said resistor in said sheath, at least a portion of the length of said terminal member being free of said embedding refractory material and accessible through the open end of said sheath, a tubular fitting non-rotatably secured to the open end of said sheath and continuing the tubular length of said sheath, said tubular fitting being adapted to extend through a wall, a terminal extension secured to the said terminal member and extending outwardly from the open end of said sheath and through said tubular fitting, at least a part of said terminal extension being irregular in cross-section, a refractory material embedding at least a portion of the irregular cross-sectional part of said terminal extension and thereby holding said terminal extension against rotation relative to said sheath, a seal for the open end of said tubular fitting, an external flange on said tubular fitting adapted to engage one face of a wall through which the tubular fitting extends, and an external threaded section on said tubular fitting in advance of said flange for receiving a nut for drawing said flange into sealing relation with said wall face.

6. An electric heater comprising a tubular sheath, an electrical resistor disposed within said sheath, electrical insulating material holding said resistor electrically insulated from said sheath and stopping short of the opening of said sheath to form a pocket, said resistor having a terminal extending through said pocket and outwardly of said sheath and said terminal having portions interlocking with said electrical insulating material to hold said terminal against movement, sealing material disposed within said pocket and about the adjacent portion of said resistor terminal, an apertured rigid plug fitting over said resistor terminal and within said pocket and against said sealing material, and fastening means interengaging with said resistor terminal outwardly of said sheath and bearing against said plug to force the latter against said sealing ma-

terial and thereby press said sealing material into sealing engagement with adjacent surfaces of said sheath and said resistor terminal.

7. An electric heater comprising a tubular sheath, an electrical resistor disposed within said sheath, electrical insulating material holding said resistor electrically insulated from said sheath and stopping short of the opening of said sheath to form a pocket, said resistor having a threaded terminal extending through said pocket and outwardly of said sheath and said terminal having flattened portions interlocking with said electrical insulating material to hold said terminal against rotation, sealing material disposed within said pocket and about the adjacent portion of said resistor terminal, an apertured rigid plug fitting over said resistor terminal and within said pocket and against said sealing material, a nut threaded on said terminal and bearing against said plug, said nut being capable of threading action to force said plug against said sealing material and thereby press said sealing material into sealing engagement with adjacent surfaces of said sheath and said resistor terminal.

8. An electric immersion heater adapted to be supported from the wall of a container, comprising a tubular sheath having exterior screw threads extending inwardly from an open end thereof and also having an abutment spaced inwardly from said end, an electrical resistor disposed within said sheath, electrical insulating material holding said resistor electrically insulated from said sheath and stopping short of said open end to form a pocket, said resistor having a threaded terminal extending through said pocket and outwardly of said open end and said terminal having flattened portions interlocking with said

electrical insulating material to hold said terminal against rotation, sealing material disposed within said pocket and about the adjacent portion of said resistor terminal, an apertured rigid plug fitting over said resistor terminal and within said pocket and against said sealing material, a nut threaded on said terminal and bearing against said plug, said nut being capable of threading action to force said plug against said sealing material and thereby press said sealing material into sealing engagement with adjacent surfaces of said sheath and said resistor terminal, the threaded end of said sheath being adapted for disposal through an aperture in said container wall whereby said abutment engages one wall surface of said container wall and the threaded end of said sheath being adapted to receive a nut disposed on the opposite wall surface of said container for drawing said abutment against said one wall surface.
